UNITED STATES PATENT OFFICE

ROYAL S. PERSHING, OF FORT WORTH, TEXAS.

HEATING DEVICE FOR OIL WELLS.

Application filed October 3, 1922. Serial No. 592,055.

To all whom it may concern:

Be it known that I, ROYAL S. PERSHING, a citizen of the United States, residing at Fort Worth, in the county of Tarrant and State of Texas, have invented certain new and useful Improvements in Heating Devices for Oil Wells, of which the following is a specification.

This invention relates to improvements in electric heating devices used in the process of applying heat by electrical means to the oil bearing rocks or sands of oil wells for the purpose of removing deposits, accretions or accumulations of paraffin or any other waxy or gummy substances from the exposed parts of the oil producing horizons of the said oil bearing rocks or sands. The prime objects are to provide means for efficiently opening the pores of rocks or sands by melting the 10 deposits, accretions and accumulations of paraffin, or other waxy or gummy substances, and liquefying them by heat, and so restoring and increasing the flow of oil therefrom into the bore of the well; to provide a combination heating unit for applying heat for any other purpose desired where it is necessary or required under the surface of the ground for the purpose of liquefying any substance either solid, semi-solid or semi-25 liquid, for the purpose of removing them from the ground; to provide means for the purpose of heating water and generating steam underground where it is desired to use steam for such purpose; and to provide a heater for applying heat to liquids, semi-liquids, solids or semi-solids by submerging the device in the substance to be heated, the device being either fixed or movable and in each instance properly connected by means 30 of proper electric conductors to a source of electric current sufficient to operate the device.

A feature of my invention is the simplicity of construction, thus eliminating the necessity of having the many metallic contacts or connections requiring heavy insulation to prevent the grounding or shorting of the electric current when the electric heating device is in operation.

Another feature of my invention is the assembly therein of a series of interchangeable heating elements or units each producing the same amount of resistance and each properly insulated and so arranged and con-

nected with the conductors which supply the electric current consumed that the maximum amount of heat may be produced from the electric current passing through the resistance elements of the several heating elements or units.

Another feature of my invention is the provision of a necessary capacity to generate and produce whatever amount of heat may be required to meet the needs of the work to be done, by either increasing the size of the heating elements or units or increasing the number thereof, or by doing both.

Another feature of my invention is the provision therein of a means whereby the several elements and parts entering into the construction of the apparatus shall be those best suited for the several purposes in which their service is required, viz.: for the outer shell or container, pure copper; for the heating elements, a proper alloy having suitable resistance for the amount of current used; for the supporting and holding in place of the heating elements, a properly constructed support for the muffles and a supporting member, both composed of insulating material; and for the conductors, the proper size copper rods.

Another feature is the provision of the particular means for supporting and maintaining in their proper position and relation to each other, the several heating elements or units comprising the heater itself. This result is obtained by the particular form and shape of the muffles upon which are wound the heating elements, said muffles at the same time provide perfectly aligned and insulated conduits for the copper conductors, which carry the electric current to the several heating elements or units comprising the heater; and the form or shape of the supporting members which are interposed between each of the muffles, and between them and the ends of the shell or container.

Another feature is to provide in the supporting members suitable ports, opening into the conduits for the copper conductors, one in each end thereof and on opposite sides thereof, to provide free and easy access to the copper conductors in order that proper connections can be made thereto by the wires connecting the heating elements or units therewith.

Another feature is to provide the neces-

sary supporting members properly adapted for the purpose and so arranged and assembled that all the expansion caused by applying heat thereto, will be permitted without causing disarrangement thereof or interference with the proper operation of the heater.

Another feature is to provide two suitable conduits, passing thru and enclosed by 10 the muffles; and the several supporting members properly aligned with each other wherein the copper conductors may be enclosed and insulated and allowed to pass thru the body of the heater connecting the 15 terminals thereof with the several heating elements or units; and said conduit at the same time permitting the copper conductors to hang freely therein from their connections with the terminals which support them 20 and in this manner providing allowance for expansion without any danger of buckling.

Another feature is to provide a suitable shell or container to enclose and protect the several member composing the necessary 25 elements comprising the heater assembly; for this purpose a copper container of suitable length and diameter and thickness being used. It may be either threaded on both ends for attaching a suitable cap or plug 30 thereto, or constructed with a band collar or lug welded or otherwise attached to the outside of the container, for the purpose of forming an attachment or seat for a clamp or clamps; and a recess or recesses may be 35 made therein wherein the end or ends of the clamps may engage, to prevent danger of being dislocated when in use, and when holding the two covers or caps closing the shell or container. The ends of the shell or container are intended to be extended a suitable 40 distance beyond the band collar or lug, and engage and enter a groove in the caps or covers used to complete the tube.

Another feature is to provide suitable 45 caps or covers for closing the ends of the shell or container which will properly seal it and render it impervious to air, gas or liquids with which it may come in contact, and allow and provide for proper openings 50 for the entrance of the terminals connecting to the electric conductors and provide a means for connecting with the cable or cables needed to operate the heater, by lowering it into the well to the position required or in withdrawing it therefrom, it being intended that a groove corresponding to the size of the end of the shell or container shall be provided to engage it therein and that a packing 55 of asbestos shall be placed therein to provide suitable packing for the joint or connection. In case it is desired to use a threaded cap for closing the ends of the shell or container, the ends of the shell or container shall be 60 threaded and the caps or covers similarly 65

threaded to engage the threaded ends, also it is intended that a threaded collar shall be first screwed onto the ends of the shell or container, the side of which would be next to the cap or cover being cut out forming half of a V shaped opening, the part of the end or cover following the band or collar already screwed on to the end of the shell or container forming the other half of the V shaped opening and when abutted together this opening is filled with packing thus providing for added security in closing the joint against air, gas or liquids which may be encountered. The cap or cover forming the top is composed of two 70 pieces, one machined to the proper thickness and with a grooved joint fitted to the end of the shell or container, with the necessary openings for admitting the terminal connection; the other piece consisting of a cap, with a sufficient part of the same cut away to allow the terminals opening in the first piece full clearance passing out, and the shoulder left to be machined to fit the top 75 of the other piece making a ground joint therewith when screwed into place on the end of the shell or container, and being also fitted for the same packing joint as described for the other end. Or the cap 80 may be held in place by clamping means fitted to engage the collar or lugs attached to the shell or container and engaging therewith, connected to a cross member thru which cross member there is a threaded hole, and into which threaded hole a threaded bolt is 85 screwed against the cap or cover engaging a depression in the cap or cover to seat the end of the bolt and so holding both in proper alignment with each other and the end of the container, and providing means for applying pressure to bring them together and close the end of the container.

The principle of the invention may be more clearly understood taken in connection with the drawings attached hereto, 110 wherein:

Figure 1 is a side elevational view of the assembly of the entire device, with a part of the containing copper cylinder cut away to show the arrangement of the interior, 115 and a cross sectional view of the cylinder cap, and means of support of the device.

Figure 2 is a side elevational view of the supporting and coil-bearing elements of the heating unit, with part cut away to show 120 a cross-section of both element.

Figure 3, is a fragmentary cross-sectional view showing the cylinder cap in its relation to the cylinder, when in place upon it; and also the terminal connection of the copper conductors supporting the heating units.

Referring more in detail to the accompanying drawings 1 indicates the casing or tube which houses the heating units, and 125

is preferably composed of copper. The lower end of the casing is closed by a cap 1' while the upper end has secured thereto a closure cap 8, thereby providing a tight jointed casing for inclosing the several heating units.

Each heating unit consists of a pair of heads or sections 2 having their opposing faces recessed, as at 2' to receive the adjacent ends of an interposed core 3 of insulating material. This core is preferably cylindrical and has its periphery spirally grooved to form a spiral seat to receive the coils, wrappings, or windings, of the resistance wire *a*. At diagonally opposite points each head 2 is provided with a pair of recesses or pockets *d* and *e*. In the preferred form of the heads and cores are alternately arranged and in their nested relation are provided with a pair of registering openings through which the conductor rods 4 extend, said rods being exposed only where they pass through the pockets *d* or *e* such provision being made to facilitate the electrical connection between the conductor rods and the respective ends of the heating coils, as indicated at *b* and *c*. The conductor rods pass upwardly through the cap 8 of insulation and also through a cross bar 7 of like material, or one insulated from the conductors, where they are connected to the supply or line wires, as indicated at 10.

A collar 6 is securely fastened to the upper end portion of casing 1 to provide a firm seating or contact between the collar and cap 8, suitable packing being provided to render the joint absolutely liquid and air tight. A pair of hooks 5 engage beneath the lower edge of collar 6 and have their upper ends attached to the cross bar 7. A clamping bolt or screw 9 is threaded through the cross bar 7 and has bearing in a caved seat formed in the upper space of cap 8.

From the foregoing it will be noted that the pair of conductor rods solely support the several heating units which are adjustable thereon and comprise the cores and heads alternately arranged in interlocking relation. The casing is closed at both ends, the upper cap 8 supporting the conductor rods and serving as a bearing for the screw 9 by which the cap is tightly clamped to the casing. The pockets *e* house the connection between the resistance elements and the rods 4 so as to provide a neat construction without having projecting loose wires.

What is claimed is:—

1. An oil well heater comprising a plurality of cores and heads alternately arranged, the opposite ends of the heads being formed with sockets to receive the adjacent ends of the adjoining cores, conductor rods passing continuously through the several cores and heads, and resistance elements supported by

the cores, the heads formed with pockets exposing the rods for connecting the elements to the rods.

2. An electric heater comprising a plurality of heads and cores alternately arranged and interlocked, a resistance element supported by each core, and conductors connected to the elements and to the heads for holding the heads and cores in their assembled relation.

3. An electric heater comprising a plurality of heads and cores alternately arranged and interlocked, a resistance element supported by each core, said heads and cores being provided with aligned openings, and conductor rods passing through the openings for connecting the cores and heads together and connected to the several resistance elements.

4. An electric heater comprising a casing, a pair of conductor rods extending lengthwise therein, a plurality of heating units supported by and connected to the rods and means for holding the units on the rods.

5. An electric heater comprising a casing, a conductor rod extending lengthwise therein, a plurality of cores slidably adjustable on the rod, a resistance element coiled about each core and connected at one end to the rod, and a head interposed between adjacent cores and housing the connection between the resistance element and the rod.

6. In a heater, a pair of heads, a core interposed between the heads and engaged therewith, a pair of electric conductor rods extending through the core and heads for holding the core between the heads, and resistance means on the core connected to the conductor rods.

7. In a heater, a pair of heads, a core interposed between the heads and engaged therewith, a pair of electric conductor rods extending through the core and heads for holding the core between the heads, and a resistance wire coiled about the core and connected at its ends to the respective rods.

8. In a heater, a pair of heads, a core interposed between the heads, a pair of electric conductor rods extending through the core and heads for holding the core between and engaged with the heads, said heads having cut-out portions to permit access to parts of the conductor wires from the exteriors of the heads, and resistance means on the core connected to the conductor rods in said cut-out portions.

9. In a heater, a plurality of cores and heads alternately arranged, resistance means on the cores, electric conductor rods extended through the cores and heads and connected to the resistance means and enclosing tube, a cap on the upper end of the tube, a collar on the tube having its upper end abutting the lower side of the cap, a cross bar above the cap, hooks carried by the cross

bar and engaged with the lower side of the collar, and a screw threaded through the cross bar and bearing upon the cap to effect adjustable engagement between the cap and collar.

10. In a heater, a plurality of cores and heads alternately arranged, resistance means on the cores, electric conductor rods extended through the cores and heads and connected to the resistance means, an enclosing tube, a cap on the upper end of the tube, a collar on the tube having its upper end abutting

the lower side of the cap, and means to adjustably connect the collar to the cap.

11. In a heater, a pair of electric conductor rods, cores threaded on the rods, a pair of heads for each core also threaded on the rods, means to hold the heads on the rods in engagement with the interposed cores, and resistance means for each core connected to the respective rods.

In testimony whereof I have signed my name to this specification.

ROYAL S. PERSHING.
